COMBINATION TOBACCO PIPE AND IGNITER

Morris J. Greenblatt, Jacksonville, Fla.

Application February 4, 1949, Serial No. 74,605

4 Claims. (Cl. 131—185)

1

This invention relates to smoking devices combined with igniters. An example of such a device is a smoking pipe portion with an igniter portion carried thereby.

An important object of the invention is to provide a combination pipe and igniter, the two being so constructed and related that the tobacco may be readily ignited, when its upper surface is closely adjacent the mouth of the bowl or is at various levels below the mouth of the bowl, without removing the igniter portion from the pipe bowl, which supports the igniter portion.

Another important object is to provide a smoking pipe having a longitudinally-extending row of spaced-apart passageways or apertures in its bowl, extending from the outer surface of the bowl to the tobacco-receiving chamber thereof, in combination with an igniter slidably longitudinally of the bowl and having a portion adapted to cover all or any one of the passageways, this portion, in conjunction with the walls of the passageways, also retaining the igniter against accidental movement longitudinally of the bowl.

Still another important object is to provide an igniter-supporting tobacco pipe, having an apertured closure for the bowl and a side apertured bowl, the apertures of the closure and bowl being adapted to permit the introduction of fire or a flame through any one of them in order to ignite tobacco within the bowl, no matter what may be the level of the tobacco within the bowl.

Despite the apertures mentioned, the tobacco is not apt to drop accidentally from the bowl of this new pipe, irrespective of any position of the latter.

Other objects and advantages of the invention will be apparent during the course of the following detailed description of the invention, taken in connection with the accompanying drawing, forming a part of this disclosure, and in which drawing:

Fig. 1 is a perspective view of the new combination smoking pipe and igniter, with the igniter portion in one of several positions with respect to the bowl of the pipe portion.

Fig. 2 is an enlarged elevation of the bowl of the pipe portion of Fig. 1 with the igniter removed.

Fig. 3 is a horizontal section, substantially on the line 3—3 of Fig. 2.

Fig. 4 is an elevation of the igniter portion as viewed facing its bowl-contacting side.

Fig. 5 is a vertical section of the bowl with the igniter portion mostly in end elevation but partly broken away in order to reveal portions of the structure beneath the wall of the igniter.

Fig. 6 is a fragmentary horizontal section of the bowl with the ignited portion attached and

2

shown in horizontal section, substantially on the line 6—6 of Fig. 5.

In the drawing, wherein for the purpose of illustration is shown a preferred embodiment of the invention and wherein similar reference characters designate corresponding parts throughout the several views, the letter A designates the combination pipe and igniter, with the pipe portion designated as B and the igniter portion as C.

10 The pipe portion B includes a conventional pipe stem 10 joining a bowl 11 which may comprise a continuous wall 12 and base 13 defining a tobacco chamber 14. The wall 12 has an outer face 15 and an inner face 16 and a portion of the generally curved face 15 may be flattened to provide a longitudinally-extending flat surface 17.

From the surface 11 to the face 16 extends a plurality of ignition passageways or apertures 18, so that they extend through the wall 12 and open into the chamber 14. They are arranged in a row extending longitudinally of the bowl, preferably as in Fig. 2.

A hinged closure 19 extends over the mouth of the chamber 14, being suitably hinged to the bowl and may be frictionally held in a mouth-closing position as by a spring clip 29 carried by the closure and bearing against the face 15. The closure 19 has its upper wall 21 spaced above the mouth of the chamber 14 and is provided with a depending skirt 22 with the free edge of the latter resting upon the end of the wall 12. The skirt 22 is provided with a plurality of spaced-apart air, flame and smoke passageways or apertures 23.

35 The igniter portion C may have much of the general construction of conventional so-called cigarette lighters, including an open-ended housing 25 carrying a wick 26 and conventional means 27 to ignite the wick to produce a fire. There is also provided a closure 28 for the open end but

40 it is preferred to hinge this closure to one end wall of the housing 25 and the side wall 29 of the housing is new in construction. This wall 29 is adapted to slidably engage the flat surface 17 of the bowl 11, and, with the bowl, provides means 30 to permit sliding of the igniter portion C longitudinally of the bowl as well as dual-function means 31 to removably retain the igniter portion C in various positions longitudinally of the bowl.

45 This means has an additional function as will be subsequently explained. The conventional fuel screw for the igniter fuel supply is shown at 35, with the screw head at 36 projecting from the wall 34 of the igniter.

50 Referring mainly to Figs. 2, 3 and 6, the means 30 includes the walls of two slots 32, extending longitudinally of the bowl, converging outwardly, and opening into the surface 17 adjacent the two

junctures of this flat surface and the curved outer face 15 of the bowl 11. The slots 32 also open into the base 13 of the bowl, as in Fig. 5. The means 30 also includes a pair of tongues 33, also shown in Fig. 4, diverging outwardly from the wall 29 of the igniter portion and adapted to be received in the slots 32 with a sliding fit, whereby the igniter portion C may be slid up and down along the bowl 11. The two tongues 33 are provided with spaced-apart slots 36' for a purpose later detailed.

The means 31 is best shown in Figs. 4 and 6 and embodies, in addition to the walls at the outer mouths of the ignition passageways or apertures 18, a plate or elongated member 37 of somewhat springy metal carried by the wall 29 above the head 36 of the screw 35, and held in place by spaced-apart projections 38 extending from the plate 37 into the slots 36' in the two tongues 33. This springy metal plate 37 is upset to provide, in the example shown, two shallow, outwardly-convex lugs or projections 39 adapted to engage the walls at the outer mouths of the ignition passageways or apertures 18 but the material of the plate is springy enough to allow the lugs or projections 39 to slip out of these mouths when the igniter portion C is manually slid longitudinally of the bowl 11. However, when one or more of the lugs 39 are in engagement with the mouth walls, the igniter portion cannot be accidentally dislodged. At the same time, the two lugs 39 provide closures for two of the flame passageways or apertures 18 and the head of the screw 35 covers the other when the igniter portion C is positioned as in Fig. 5. However, when the igniter portion C is positioned, with respect to the bowl 11 as in Fig. 1, the uppermost of the ignition passageways 18 is uncovered and axially aligned with the general longitudinal axis of a flame or fire projecting from the wick 26 and drawn into this passageway. In other words, the flame or fire is substantially within the plane of the passageway. At this time, the upper and second lugs 39 close the intermediate and lowermost flame passageways respectively. When the igniter portion C is positioned as in Fig. 5 and the closure 28 raised as in Fig. 1, the flame or fire will be drawn into one or more of the apertures or passageways 23 in the skirt of the closure 19. Thus, it is now obvious that the tobacco may be ignited in the chamber 14 no matter where the level of the tobacco may be.

Ignited particles of tobacco cannot drop from the passageways or apertures 18 if the igniter portion C is properly manipulated, the igniter portion C cannot accidentally drop from the pipe portion B yet the igniter portion C may be manually removed, as for cleaning out the passageways 18, by sliding it downwardly. It provides a means to grasp the combination device A, as when the bowl 11 is hot and when the igniter portion is slid downwardly so that its bottom face is in the same horizontal plane as the lowest portion of the base 13, the combination A may be disposed upon a flat support and will not be inclined to tip over.

Various changes may be made to the form of the invention herein shown and described without departing from the spirit of the invention or scope of the following claims.

What is claimed is:

1. In a combined tobacco pipe and tobacco igniter, a pipe portion including a bowl having an outer surface, a tobacco chamber, a pipe stem, said stem provided with an opening to said chamber, a chamber mouth and an ignition passageway extending from said outer surface to said chamber and disposed below said mouth and above said

opening, said passageway having an outer mouth; and an igniter portion, including a housing; retaining means carried by said bowl and said housing slidably mounting said housing upon said bowl; dual-function means releasably retaining said housing against accidental movement with respect to said bowl and covering the outer mouth of said passageway, when said housing is in one slidable position, and uncovering said outer mouth when said housing is in another slidable position, and means to start a fire when said housing is in the last-named position with said fire substantially within the plane of said passageway, whereby when said fire is projected through said passageway and into said chamber it will ignite tobacco within said chamber.

2. In a combined tobacco pipe and tobacco igniter, as defined in claim 1, in which said dual-function means includes a member of resilient metal carried by said housing and provided with an outwardly convex lug constructed and arranged to selectively ride into and out of said outer mouth upon selective sliding of said housing with respect to said bowl.

3. In a combined tobacco pipe and tobacco igniter, as defined in claim 1, in which said retaining means includes a pair of tongues provided with slots, said tongues extending outwardly from said housing, and said retaining means also including the walls of a pair of complementary slots, extending into said bowl from said outer surface, and in which said dual-function means includes a member of resilient metal carried by said housing, provided with an outwardly convex lug constructed and arranged to selectively ride into and out of said outer mouth upon selective manual sliding of said housing with respect to said bowl, and said member of resilient metal also being provided with a pair of projections extending into the slots of said tongues.

4. In a combined tobacco pipe and tobacco igniter, as defined in claim 1, in which said retaining means includes a pair of tongues provided with slots, said tongues diverging outwardly from and extending longitudinally of said housing, and said retaining means also including the walls of a pair of complementary slots, diverging into said bowl from said outer surface and extending longitudinally of said bowl, and in which said dual-function means includes a member of resilient metal carried by said housing, provided with an outwardly convex lug constructed and arranged to selectively ride into and out of said outer mouth upon selective manual sliding of said housing with respect to said bowl, and said member of resilient metal also being provided with a pair of projections extending into the slots of said tongues.
